UNITED STATES PATENT OFFICE

NORRIS E. GOODRICH, OF BATTLE CREEK, MICHIGAN, ASSIGNOR TO SANITARIUM EQUIPMENT COMPANY, OF BATTLE CREEK, MICHIGAN

MASSAGING MACHINE

Application filed May 10, 1928. Serial No. 276,602.

The main objects of this invention are:

First, to provide an improved massaging machine in which the operating mechanism is effectively housed within a cabinet and at the same time is fully exposed for use and manipulation.

Second, to provide a massaging machine housed within a cabinet with means for effectively bracing when in use.

10 Third, to provide a motor driven massaging machine in which the motor is supported and housed so that the operation is substantially noiseless.

Fourth, to provide a massaging machine 15 having these advantages which is attractive in appearance and at the same time highly efficient.

Objects relating to details and economies of construction and operation of my invention 20 will appear from the description to follow. The invention is defined and pointed out in the claims.

A structure which is a preferred embodiment of my invention is illustrated in the 25 accompanying drawing, forming a part of this application, in which:

Fig. 1 is a front elevation of a structure embodying the features of my invention, parts of the cabinet being broken away to 30 show the arrangement of the mechanism therein, the doors of the cabinet being open.

Fig. 2 is a fragmentary view partially in vertical section on line 2—2 of Figs. 1 and 3 with the parts adjusted to operative position.

35 Fig. 3 is a horizontal view on line 3—3 of Fig. 1.

Fig. 4 is a fragmentary front elevation of the upper portion of the cabinet when open.

In the drawings similar reference characters refer to similar parts throughout the several views.

40 In the embodiment illustrated, the cabinet comprises a main body portion designated generally by the numeral 1 open at the front and provided with doors 2.

The cabinet has a top portion comprising a fixed rear section 3 and a hinged section 4. The side and rear walls of the fixed section 3 constitute continuations or may be 45 formed integrally with the side and rear

walls of the main body portion as may be found most expedient in practice. The hinged section 4 is connected to the front edge of the fixed section by means of hinges 5 to be collapsed rearwardly thereon, as 55 shown in Fig. 2.

A shelf 6 is disposed across the cabinet with its front edge in spaced relation to the front edges of the side walls, for purposes which will appear as the description proceeds. On this shelf, I mount a housing 7 having journals 8 projecting therefrom adjacent its lower end on which the rocker arms or actuated members 9 are pivotally mounted. These actuated members are provided with hooks 10 with which the applicators may be engaged, a portion of a strap-like applicator 11 being shown in Fig. 2.

A shaft 12 is mounted in suitable bearings 13 in the side walls of the housing to 70 project therefrom, crank discs 14 being mounted on the outer ends of the shaft. These crank discs have radially adjustable crank pins 15 connected by the pitmen 16 to the upper ends of the actuated members 9. 75 These crank pins may be adjusted in the slots 16, the clamping nuts 17 being provided for securing them in their adjusted positions so that the stroke of the actuated members may be varied from maximum to minimum. 80

Below the shelf I provide a motor compartment 18, the motor 19 being mounted therein, the motor having a base 20 pivoted at 21 on a supporting plate 22 of substantial weight, it being found in practice that a base of boiler iron is satisfactory for this purpose.

This supporting plate 22 is arranged on a pad 23 of acoustical material, that is, material such as is used in deadening walls and the like. The edges of the plate are clamped by the lower edges of the side wall linings 24 of suitable resilient sound-deadening material, supporting strips 25 being arranged, in Fig. 2, to support the material 24 and at the same time hold it against the supporting plate. The door 26 of the motor compartment is also provided with a sound deadening lining 27.

The motor shaft 28 is provided with 100

stepped pulleys 29, 30 and 31 while the shaft 12 is provided with a pulley 32 preferably aligned with the central pulley 30.

A driving belt 33 serves as a suspending means for the motor on its pivot so that the 5 motor serves as a belt tightener and also may be raised and lowered to permit the shifting of the belt from one of the stepped pulleys to the other, a hand piece 35 being provided 10 to facilitate this manipulation. This suspending means also is a factor in the sound deadening so that the machine is very quiet in its operation.

To facilitate the adjustment of the crank pins, forwardly facing recesses 36 are formed 15 in the side walls 3 of the fixed portion of the top and crank projections 37 are formed on the side walls of the hinged section so that when the top is opened, free access may be had to the crank discs.

20 To brace the cabinet and also provide a platform for the operator when using the cabinet, I provide a platform 38 having rearwardly projecting arms 39 to which link-like braces 40 are connected by the pivots 41. The inner ends of these braces 40 are connected by the pivots 42 to plates 43 secured on the inner sides of the side walls 25 of the cabinet so that the braces may be swung to the vertical position, as shown by dotted lines in Fig. 2, with the platform suspended between them, or the platform may be swung to the extended operative position shown by full lines in Fig. 2 in which 30 position it constitutes an effective brace for the cabinet so that a person standing on the platform may exert a very heavy pull on the applicators without moving the cabinet or tipping it over.

35 To retain the platform in collapsed position, I provide a spring catch 44 which engages one of the braces 40 when the platform is collapsed, as shown in Fig. 1. A shelf 45 is provided to receive the applicators, one being conventionally shown at 46. When 40 the platform is collapsed the doors may be closed over the same, thereby entirely concealing the operating mechanism.

45 My improved massaging machine is very attractive in appearance, is highly efficient and is substantially noiseless when in use.

50 I have illustrated and described my improvements in an embodiment which I consider very satisfactory. I have not attempted to illustrate or describe various 55 other modifications of adaptations as I believe the disclosure made will enable those skilled in the art to embody or adapt my improvements as may be desired.

60 Having thus described my invention, what I claim as new and desire to secure by Letters Patent, is:

65 1. A cabinet for massaging machines open at the front and having a top portion comprising a fixed rear section and a front sec-

tion hinged to said fixed section to fold rearwardly thereon, the fixed section having side walls with forwardly facing recesses therein for exposing parts arranged within the cabinet when the front section is opened, 70 the front section having side walls with extensions corresponding to and closing into said recesses, a door for said cabinet, a shelf adapted to support a massaging machine disposed in said cabinet below its said top portion with its front edge in spaced relation to the door when closed, a platform, and links pivotally mounted on the inner sides of the side walls of the cabinet and pivotally connected to the platform whereby the platform may be swung to a horizontal position in front of the cabinet with the links in an upwardly inclined relation constituting braces for the cabinet, or the links may be swung to a vertical position within the cabinet with 75 the platform suspended between the same and between the said shelf and door.

2. A cabinet for massaging machines open at the front, a door for said cabinet, a shelf adapted to support a massaging machine 80 with its front edge in spaced relation to the door when closed, a platform, and links pivotally mounted on the inner sides of the side walls of the cabinet and pivotally connected to the platform whereby the platform may be swung to a horizontal position in front of the cabinet with the links in an upwardly inclined relation constituting braces for the cabinet or the links may be swung to a vertical position within the cabinet with 85 the platform suspended between the same and between the said shelf and door.

3. A cabinet for massaging machines open at the front and having a top portion comprising a fixed rear section and a front section hinged to said fixed section to swing rearwardly, the fixed section having side walls with forwardly facing recesses therein for exposing parts arranged within the cabinet when the front section is opened, the front section having side walls with extensions corresponding to and closing into said recesses, a door for said cabinet, a shelf adapted to support a massaging machine disposed in said cabinet below its said top portion with 105 its front edge in spaced relation to the door when closed, a platform, and a link pivotally mounted within the cabinet and pivotally connected to the platform whereby the platform may be swung to a horizontal position in front of the cabinet with the link in an upwardly inclined relation constituting a brace for the cabinet, or the link may be swung to a vertical position within the cabinet with the 110 platform suspended between the said shelf and door.

4. A cabinet for massaging machines open at the front and having a top portion comprising a fixed rear section and a front section hinged to said fixed section to swing 115

120

5 rearwardly, a door for said cabinet, a shelf
adapted to support a massaging machine dis-
posed in said cabinet below its said top por-
tion with its front edge in spaced relation to
the door when closed, a platform, and a link
pivotally mounted within the cabinet and
pivotally connected to the platform where-
by the platform may be swung to a horizontal
10 position in front of the cabinet with the link
in an upwardly inclined relation constituting
a brace for the cabinet or the link may be
swung to a vertical position within the cab-
inet with the platform suspended between
the said shelf and door.

15 5. A cabinet for massaging machines open
at the front, a platform provided with rear-
wardly projecting arms, links pivotally
mounted on the inner side of the side walls
20 of said cabinet and to the rear ends of said
arms on said platform whereby the platform
may be swung to a horizontal position in
front of the cabinet with the links in an up-
wardly inclined relation constituting braces
25 for the cabinet or the links swung to a ver-
tical position within the cabinet with the
platform suspended between the same, a
catch coacting with one of said links when the
platform is collapsed, and doors for the cab-
inet closing over the platform.

30 6. A cabinet for massaging machines open
at the front, a platform provided with rear-
wardly projecting arms, links pivotally
mounted on the inner side of the side walls of
35 said cabinet and to the rear ends of said arms
on said platform whereby the platform may
be swung to a horizontal position in front of
the cabinet with the links in an upwardly in-
clined relation constituting braces for the
40 cabinet or the links swung to a vertical posi-
tion within the cabinet with the platform sus-
pended between the same, and doors for the
cabinet closing over the platform.

45 7. A cabinet for massaging machines open
at the front, a platform provided with rear-
wardly projecting arms, links pivotally
mounted on the inner sides of the cabinet side
50 walls and pivotally connected to said plat-
form whereby the platform may be swung to
a horizontal position in front of the cabinet
with the links in an upwardly inclined rela-
tion constituting braces or the links swung to
55 a vertical position within the cabinet with the
platform suspended therefrom, and a closure
for said cabinet closing over the platform.

55 8. A cabinet for massaging machines open
at the front, a door for said cabinet, a plat-
form, and a link pivotally mounted within
the cabinet and pivotally connected to the
60 platform whereby the platform may be swung
to a horizontal position in front of the cab-
inet with the link in an upwardly inclined rela-
tion constituting a brace for the cabinet or
the link may be swung to a vertical position
65 within the cabinet with the platform sus-
pended within the cabinet.

9. A cabinet for massaging machines open
at the front and having a top portion com-
prising a fixed rear section and a front sec-
tion hinged to said fixed section to swing
70 rearwardly, the fixed section having side
walls with forwardly facing recesses therein
for exposing parts arranged within the cab-
inet when the front section is opened, the front
75 section having side walls with extensions cor-
responding to and closing into said recesses,
and a door for said cabinet.

In witness whereof I have hereunto set my
hand.
